FIG_1

FIG_2

FIG_3

FIG_4

FIG. 1 is a perspective view of an incense burner, showing my new design;

FIG. 2 is a side elevational view thereof, all sides being the same;

FIG. 3 is a top plan view; and

FIG. 4 is a bottom plan view.

In FIGS. 1 and 2, the cross-hatching pattern which is partially shown is understood to repeat uniformly across the circumscribed area.

I claim:

The ornamental design for a incense burner, substantially as shown and described.
